UNITED STATES PATENT OFFICE.

HANS L. B. SCHRECK, OF WHEELING, WEST VIRGINIA.

SHEET OR ANNEALING FURNACE.

Application filed January 27, 1922. Serial No. 532,319.

To all whom it may concern:

Be it known that I, HANS L. B. SCHRECK, residing at Wheeling, in the county of Ohio and State of West Virginia, a citizen of the 5 United States, have invented or discovered certain new and useful Improvements in Sheet or Annealing Furnaces, of which improvements the following is a specification.

Difficulty has been experienced in the operation of sheet heating or annealing furnaces in which the sheets are moved through the furnace by rollers, in maintaining the sheets central. The feed rollers are generally cylindrical and unless the sheets are carefully placed in the furnace they will move to one side or the other of the furnace, and their movement checked or retarded; and further, as it is the general practice to construct the rollers with a jacket or covering of 10 fine clay, they are rapidly cut by the sheets so that some portions of the rolls will have a smaller diameter than the other portions and the sheets will move laterally onto the portions having the larger diameter.

It has been attempted to prevent lateral movement of the sheets by employing concave rolls, the middle portions being smaller in diameter than the ends. But unless the sheets are accurately placed on such rolls, 20 i. e., with the center line of the sheet in line vertically with the smallest diameter of the roll, the sheet will move laterally; and further, in case of a more rapid reduction in diameter of one portion of such roll, the sheet 25 will be drawn laterally by the larger portion of the roll.

The object of the invention described herein is to provide for the maintainance of the sheet in proper central position if properly fed into the furnace, and also to move the sheet laterally into such central position in case it has not properly started into the furnace. It is a further object of the invention to prevent excessive heating of the 40 rollers and consequent rapid cutting away of their surfaces by the sheets. The invention is hereinafter more fully described and claimed.

In the accompanying drawings forming a 50 part of this specification, Fig. 1 is a sectional plan view of a sheet heating furnace having my improvement therewith combined; Fig. 2 is a sectional elevation, the plane of section being indicated by the line II-II, Fig. 1; Fig. 3 is a view similar to Fig. 2 illustrating 55 a modification of the improvement; Fig. 4 is

a sectional elevation of my improved feed roller; Fig. 5 is a view in elevation of the skeleton for such roller when a jacket of refractory material is employed; and Fig. 6 60 is a transverse section on a plane indicated by the line VI-VI, Fig. 5.

In the practice of the invention the furnace is constructed in the usual or any suitable manner, with doors at each end for the 65 charging and removal of the sheets to be heated. The furnace may be heated by any suitable means using solid, liquid, or gaseous fuel. On each side of the furnace are arranged a series of bearings for the shafts 2 70 of the rolls, which may be driven by intermeshing gear wheels on the shafts 2 or by chains engaging sprocket wheels on the shafts.

As shown, the rolls are made conical and 75 are oppositely arranged in the furnace, i. e., the large end of one roll being at one side of the furnace and the large end of the next roll being on the opposite side of the furnace. The peripheral speed of the larger 80 end of the rolls being greatest, it will tend to cause a lateral movement of the portion of the sheet in contact therewith, but when such portion has passed to the next roller, the latter will tend to cause an opposite lateral movement of the sheet, so that one roll 85 will correct any lateral displacement due to the action of the preceding roll.

As shown, these rolls may be arranged with the axes of the rolls in the same horizontal plane as shown in Fig. 3, so that when a sheet rests thereon, it will be transversely curved, as in this condition the sheets will 90 present greater resistance to drooping when passing out of the furnace. In lieu of arranging the rolls with their axes in the same horizontal plane as above stated, they may 95 be arranged with the axes at such an angle that the upper portions of their peripheries will be in a horizontal plane, as shown in 100 Fig. 3.

It is preferred to construct the rolls as shown in Figs. 4, 5, and 6. The shaft of the roll consists of two pipe sections 2 and 2^a having their inner ends closed preferably 105 by welding such ends to opposite sides of a disc 3 thereby preventing the flow of the cooling medium, as water, through the hollow shaft. These pipe sections are connected by a plurality of pipes 4 having 110 their ends bent inwardly so that the portions intermediate such ends will be spaced suit-

able distances from the shaft, such distances being dependent on the desired diameter of the roll. It is preferred that the ends of the pipe sections should be welded 5 to the shaft sections and it is also preferred that the disc 3 should be made of such diameter that the pipes 4 will rest in notches in the periphery of the disc, which will then serve to prevent any lateral or inward flexure of the pipes.

It will be readily understood that by employing a sufficient number of pipes 4, say five, six or more, such skeleton roll may be used for feeding the sheets, but if preferred, 15 this skeleton may serve to support a jacket of refractory material as shown in Fig. 4. The jacket may be formed by a number of hollow sections 5; these sections which are provided interiorly with radial notches for 20 the reception of the pipes 4, consist of sections having their ends constructed to project one into the other. These sections are slipped endwise onto the skeleton and are held in position by nuts 6, screwing onto 25 threaded enlargements of the shaft section. It is preferred that two adjacent sections of the jacket should be spaced apart to compensate for expansion and contraction, and in order to prevent any moving back and forth 30 of the sections, springs 8 are interposed between the disc 3 and plates 9 movable along the shaft sections and bearing against internal shoulders in the jacket sections.

I claim herein as my invention:

35 1. A feed roller for furnaces having in combination a shaft having hollow end portions, and bent pipe sections having their ends connected to the hollow portions of the shaft.

40 2. A feed roller for furnaces having in

combination a hollow shaft, bent pipe sections having their ends connected to the shaft, and means arranged intermediate the points of connection of the pipes with the shaft for preventing the flow of cooling 45 fluid through the shaft.

3. A feed roller for furnaces having in combination a shaft consisting of hollow sections, a metal disc interposed between adjacent ends of the shaft sections, bent pipes 50 having their ends secured to the respective shaft sections in opposite sides of the disc.

4. A feed roller for furnaces having in combination a shaft consisting of hollow sections, bent pipes having their ends secured 55 to the respective shaft sections, and a disc interposed between adjacent ends of the shaft sections and adapted to support the pipes at points intermediate their ends.

5. A feed roller for furnaces having in 60 combination a shaft consisting of hollow sections, bent pipes having their ends secured to the respective sections, the intermediate portions of the pipes being spaced from the shaft, and a jacket of refractory 65 material supported by the pipes.

6. A feed roller for furnaces having in combination a shaft consisting of hollow sections, a disc interposed between adjacent ends of said sections, bent pipes having their 70 ends secured to the respective sections, tubular blocks adapted to be supported by the pipes, adjustable abutments on the shaft sections for holding the blocks in position and springs for holding the blocks in contact while permitting expansion of the blocks.

In testimony whereof, I have hereunto set my hand.

HANS L. B. SCHRECK.
